UNITED STATES PATENT OFFICE.

JOHN W. HENRY, NEW YORK, N. Y.

HAIR-CUTTER.

1,391,635.

Specification of Letters Patent. Patented Sept. 20, 1921.

Application filed August 23, 1920. Serial No. 405,233.

To all whom it may concern:

Be it known that I, JOHN W. HENRY, a citizen of the United States of America, residing at New York, in the county of New York and State of New York, have invented certain new and useful Improvements in Hair-Cutters; and I do declare the following to be a full, clear, and exact description of the invention, such as will enable others skilled in the art to which it appertains to make and use the same.

This invention relates to improvements in hair cutters.

One object of the invention is to provide a device of the above mentioned character which is of such construction that it may be held in one hand and guided over the head while the cutting means is actuated by manually controlled means with the other hand, thus producing a device of considerable utility for both experienced and inexperienced barbers.

Another object of the invention is to provide hair cutters provided with means for spacing the cutting means from the head, this spacing means being such that it does not interfere with the effective movement of the device over the head and being so mounted that it may be moved to a position which is entirely out of the way when it is not desirable to use it.

A further object of the invention is to provide hair cutters equipped with the above mentioned novel spacing means which is so positioned that it serves as a fulcrum, whereby the cutting teeth may be quickly and easily tilted toward or from the hair, thus enabling the operator, especially if he is inexperienced, to move the device to the most advantageous angle to effectively cut the hair.

A still further object of the invention is to provide a device of the above mentioned class which is an improvement upon all prior devices; one which is extremely simple in construction, strong, durable, and in expensive to both the manufacturer and the user.

Other objects and advantages of the invention will be apparent during the course of the following description.

In the accompanying drawings forming a part of the specification and in which like numerals are employed to designate like parts throughout the same:

Figure 1 is an elevational view, with parts

in section, of a hair cutter constructed in accordance with my invention;

Fig. 2 is a central transverse section thereof;

Fig. 3 is a top plan view thereof.

Referring to the drawings wherein the preferred construction of my device is illustrated, the numeral 1 designates a plate provided along one of its edges with a plurality of curved teeth 2. This plate may be conveniently and correctly termed the stationary cutter. Movable longitudinally across one face of the stationary cutter is the movable cutter 3 which is also provided with a plurality of curved teeth 4 which coact with the first named teeth 2. To guide the movable cutter and to retain the two cutters in correct operative relation, I provide the stationary cutter with one or more screw threaded projections 5 which extend through the longitudinal and centrally disposed slot in the movable cutter 3, the two cutters being retained together by means of the nuts which are threaded onto the ends of said studs. With this construction it is obvious that the proper friction between the two cutters may be obtained and the movable cutter may be made to move with a greater or less facility by adjusting the nuts on the ends of the studs 5.

As before intimated, my improved hair cutter includes manually operated means for actuating the cutters. This means, of course, could be of any construction and could be mounted in any suitable way. By preference however, it comprises a pair of intermeshing gears 6 and 7 which are mounted on the extended part of the stationary cutter plate 1, one of these gears 7 being provided with a beveled gear portion which coacts with the small bevel gear 8 which is rotated by the hand crank 9. To properly position the hand crank and gear 8, I provide the stationary cutter plate with a laterally extending flange 10, one of which is provided with a board projection 11 which constitutes a bearing for a portion of the hand crank 9 in the manner disclosed clearly in Fig. 1. To impart motion to the movable cutter, I make use of a link 12 which is connected to the movable cutter and is also eccentrically connected to the gear 6.

To exclude dust and to protect the gearing and movable parts of the device, I provide a removable cover 13 which fits over the flanges 10 of the stationary cutter in the

manner disclosed. This cover will, of course, be provided with a slot 14 for the reception of the bearing 11. The efficiency of the device is increased by the employment 5 of a detachable handle 15. By removing the handle, the device may be placed in as small and compact package as may be desirable.

It has been previously pointed out that my 10 device may be effectively used by inexperienced and other barbers. To this end, I have employed novel spacing means which also serves as a fulcrum for the device. This spacing means is here shown in the form of 15 pivotally mounted rollers 16 which are carried by the stationary cutter and are arranged on one of the faces of the latter at spaced intervals. These rollers which are carried by forks connected to laterally extending integral studs projecting from the 20 rear face of the stationary cutter may be swung out in position for use as disclosed in Fig. 2, or they may be folded back against the device when not in use and will thus be 25 entirely out of the way. Bolts serve to pivotally connect the aforesaid forks to the studs and also retain the rollers in either operative or inoperative position. By employing rollers for this purpose, the device may be very 30 easily and effectively moved over the head. As before stated, the rollers 16 serve as fulcrum means, that is, when swung out to operative position and rested against the head, they will permit the cutting teeth to be readily 35 tilted toward or moved away from the hair to obtain the proper and most effective cutting angle.

In cutting hair, it is customary to employ 40 a comb and since much time is wasted in picking up and laying down the comb when it is necessary to use it, I attach a comb 17 to the cover plate 13 so that it will always be in a good position for quick use.

The operation of the device is as follows: 45 The operator grasps the handle 15 in one hand, moves the device over the head in the usual manner and at the same time rotates the hand crank 9 to operate the cutters. Should the operator be inexperienced, he 50 may obtain the proper spacing of the device from the head by making use of the novel spacing rollers 16. With these rollers he may also readily and easily tilt the device toward or from the head to gain the most 55 advantageous angle for cutting the hair. Should it be desired to make use of the comb, it is only necessary to reverse the de-

vice to bring the comb into position for operation. When the device is not in use, the handle may be detached and it may be 60 conveniently and compactly packed away.

From the foregoing description it will be seen that I have perfected an extremely simple and advantageous cutter which is not only inexpensive and convenient and easy to 65 operate, but is highly effective in operation since it is equipped with means to enable an inexperienced barber to properly space the cutters from the hair and to easily and effectively guide the device over the head by 70 employment of said spacing means. The above and other advantages have, no doubt, become apparent from the foregoing description.

A careful consideration of the description 75 taken in connection with the accompanying drawings will enable persons skilled in the art to which this invention pertains to obtain a clear understanding of the same, therefore, further description is deemed unnecessary.

Since effective and advantageous results may be obtained with the foregoing construction and arrangement of parts, this construction and arrangement is taken as a 85 preferred embodiment of my invention. However, I wish it to be understood that various minor changes in the shape, size, and arrangement of parts may be resorted to without departing from the spirit of the invention or the scope of the subjoined claim. 90

I claim:

A device of the class described comprising a comparatively long stationary cutter plate provided at one end with a laterally extending flange which is in turn provided with a bearing, laterally extending screw-threaded studs carried by said plate, being disposed near the center thereof, a movable cutter 95 slideable against the first named cutter and provided with a slot through which said studs extend, nuts on the threaded ends of said studs, intermeshing gears arranged on the first named cutter plate adjacent the aforesaid flange, a driving gear meshing with one of the first named gears and being disposed at right angles thereto, a shaft 100 journaled in the aforesaid bearing, a hand crank connected with said shaft for rotating the latter, and a driving connection between 105 said gears and movable cutter.

In testimony whereof I have hereunto set my hand.

JOHN W. HENRY.
